UNITED STATES PATENT OFFICE.

CARLOS C. KING, OF INDIANAPOLIS, INDIANA.

DUMP-WAGON.

1,143,405.

Specification of Letters Patent. Patented June 15, 1915.

Application filed March 23, 1914. Serial No. 826,691.

To all whom it may concern:

Be it known that I, CARLOS C. KING, a citizen of the United States, residing at Indianapolis, in the county of Marion and State of Indiana, have invented a new and useful Dump-Wagon, of which the following is a specification.

This invention relates to dump wagons, one of its objects being to provide a wagon 10 of this type utilizing a body capable of rotating about its longitudinal axis in either direction, thus to dump the contents thereof, the said body being so weighted as to return automatically to its normal or active 15 position after the discharge of its contents.

A further object is to provide simple 20 means for locking the body against rotation, said means being readily actuated for the purpose of releasing the body to swing to either side.

Another object is to provide a wagon of this type which can be steered at either end, thus being easily guided when moved either 25 forwardly or rearwardly.

25 A further object is to provide a dump wagon the body of which is supported close to the ground and can be of much greater capacity than the ordinary wagon bodies.

30 With the foregoing and other objects in view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

40 In the accompanying drawings the preferred form of the invention has been shown.

In said drawings:—Figure 1 is a side elevation of the dump wagon, the near wheels 45 being removed and their spindles being shown in section. Fig. 2 is a plan view of one end portion of the wagon. Fig. 3 is an end elevation of the wagon, one of the 50 positions of the body while moving to dumping position, being indicated by dotted lines. Fig. 4 is a vertical longitudinal section through a portion of the wagon. Fig. 5 is a section on line A—B Fig. 4.

55 Referring to the figures by characters of reference 1 designates the axles supported by wheels 2 and arranged above each axle

is a bolster 3, each axle being connected to the bolster thereabove by a king bolt 4, each bolt extending through a socket member 5 and a ball member 6 which coöperate 60 to form a bearing for the bolster thereabove. Each king bolt also engages a tongue 7 extending into a slot 8 in the bolster, this tongue constituting a part of a bracket 8 which is secured upon a 65 tongue 9 extending outwardly from the axle 1 at right angles thereto. An upwardly extending shaft 10 is journaled in the bracket 8 and has secured to it diverging chains 11 attached to the adjacent bolster 3. Each 70 shaft 10 may be rotated in any suitable manner, as by means of a hand wheel 12 so that one chain 11 can thus be paid out while the other is being taken up and, consequently, the tongue 9 and the axle to which it is secured will be caused to swing toward the 75 right or to the left as desired. Braces 13 may connect the sides of the tongue 9 to the end portion of its axle 1.

The end portions of the two bolsters 3 are 80 connected by side beams 14, the end portions of these side beams being extended downwardly to the bolsters while the intermediate portions of the side beams are at such elevations as to allow the wheels 2 to 85 swing partly thereunder and thus permit a comparatively short curve to be effected.

Each bolster is provided adjacent its center, with a bearing 15. These bearings receive trunnions 16 extending from the 90 ends of the body 17 of the wagon. This body is preferably substantially trough-shaped and has a weight 18 secured along the bottom thereof so that the open top of the body will be held normally uppermost. 95 The body can be made of any desired material but is preferably formed of sheet metal suitably reinforced.

Upstanding from each bolster 3 are spaced segments 19 concentric with the 100 trunnions 16, these segments being disposed in pairs. Pivotaly mounted between the segments of each pair are dogs 20 located close to but at opposite sides of the center of the segments and having a sufficient space 105 between them to receive a pin 21 projecting from the end of body 17 close to the open top thereof. Each dog 20 has an upstanding ear 22 and the pivot pin 23 which extends through each dog at that end thereof from the pin engaging end of the dog, serves not only to hold the dog 20

to the segments 19 but also to secure to said segments a guide yoke 24.

Journalized on each of the beams 14 is a longitudinal shaft 25 and extending from each end of each of these shafts is a crank arm 26. A chain 27 extends from each crank arm and upwardly through the adjacent guide yoke 24 to the ear 22 on the adjacent dog.

10 It will be apparent that under ordinary conditions, while the dogs 20 are in their normal positions, as shown in Fig. 5, the body 17 of the wagon will be held upright so that material contained therein will not be discharged. Should it be desired to 15 empty the body 17 by turning said body to the right, one of the crank arms 26 at the right of the wagon is pushed outwardly and downwardly, thus causing the chains 27 connected to the actuated crank arm 26 to pull on the dogs to which they are secured. These dogs will thus be swung upwardly 20 out of the paths of the pins 21 and the body 17 will thus be free to swing laterally and downwardly to the right until it assumes an inverted position at which time the said 25 body will be emptied of its contents. As soon as all of the contents of the body have been discharged, said body will gravitate 30 back to its normal position under the action of the weight 18 and, as the dogs 20 are returned to their normal position by gravity as soon as the crank arms 26 are 35 restored to their normal positions, it will be apparent that during the return movement of the body 17, the pins 21 will elevate the dogs 20 in the paths thereof and 40 assume positions between the dogs as shown in Fig. 5. Thus the body will be again in position for further use. Obviously, the body can be rotated to the left as readily as to the right by actuating the proper crank arms 26 and dogs 20.

The wagon herein described can be used 45 in connection with excavators and can be

propelled by tractors or the like. It has also been found useful in grading and in hauling stone, gravel or other material used in road building. As the wagon is provided at each end with steering mechanism, it can 50 be guided with equal facility whether pushed or pulled and can thus be easily moved back and forth along narrow paths.

What is claimed is:—

1. The combination with connected bolsters and segments disposed in pairs upon the respective bolsters, of a body supported by and between the bolsters and mounted for rotation about a longitudinal axis, opposed dogs movably mounted between the 60 segments, means outstanding from the ends of the body for engagement with the dogs to hold the body against rotation, and separate means for actuating the dogs to release the body for rotation in either direction out 65 of normal position.

2. A dump wagon including bolsters, side beams connecting the bolsters, a revoluble body having trunnions at its ends journalized upon the bolsters, segments disposed in pairs, the said pairs being connected to the respective bolsters and being concentric with the trunnions, opposed dogs pivotally mounted between the segments of each pair, outstanding projections upon the body and adapted to project between the dogs to hold the body against rotation, a shaft journalized on each side beam, means for rotating the shaft, and flexible connections between each shaft and the adjacent dogs for shifting the 75 dogs out of holding positions when the shaft is rotated.

In testimony that I claim the foregoing as my own, I have hereto affixed my signature in the presence of two witnesses.

CARLOS C. KING.
